UNITED STATES PATENT OFFICE.

EDWARD L. SNYDER, OF BROOKLYN, NEW YORK.

DESIGN FOR A SOAP DISH OR HOLDER.

SPECIFICATION forming part of Design No. 26,352, dated December 1, 1896.

Application filed October 29, 1896. Serial No. 610,513. Term of patent 14 years.

To all whom it may concern:

Be it known that I, EDWARD L. SNYDER, a citizen of the United States, residing at Brooklyn, in the county of Kings and State of New York, have invented and produced a new and original Design for a Soap Dish or Holder, of which the following is a specification, reference being had to the accompanying drawings, forming a part thereof, in which—

Figure 1 is a perspective view of a soap dish or holder embodying the features of my design. Fig. 2 is a longitudinal section on the line 2 2 of Fig. 3, and Fig. 3 is a transverse section on the line 3 3 of Fig. 2.

The leading feature of the design consists of the top A, that slopes downward from its margin to a central opening a, and the body

B, which appears hollow and has an opening b above its base, which exposes a portion of the body-chamber.

The minor feature of the design consists in the flange C at the junction of the body with the top, the flange constituting a portion of the top, and in the oppositely-arched walls of the body-chamber, the two arched surfaces meeting at the side walls or portions of the said chamber.

I claim—

The design for a soap dish or holder, herein shown and described.

EDWARD L. SNYDER.
